SURGICAL CAST CUTTER

Arthur J. Hood, Reno, Nev.

Application December 27, 1943, Serial No. 515,641

2 Claims. (Cl. 30—229)

This invention relates to implements for cutting or shearing surgical castings, and particularly represents improvements over the implement shown in my co-pending application for patent, Serial No. 511,145, filed November 20, 1943, now Patent No. 2,357,197, issued August 29, 1944.

The principal objects of the present invention are to provide a cast cutting implement so constructed that it can get under the cast and cut close to the skin without bruising or otherwise hurting the tender flesh of the patient, so that it is well adapted to remove non-padded casts; one which can be manipulated to remove punched-out sections of the cast or to cut a non-severed ribbon in the cast, as may be desired; and which has a greater cutting leverage than the previous device so that cutting operations are facilitated and expedited without the need of excessive physical effort on the part of the operator.

Another object is to provide a cutting implement of this character so constructed that the lower handle is integral or rigid with the lower jaw or shoe and said handle forms the means to guide said jaws in any direction in which it is desired to make a cut in the cast, and also makes it very easy to initially insert the implement between the cast and the flesh and facilitate starting of the cut, as well as the subsequent cutting movements.

Another object of the invention is to provide a simple and inexpensive device, and yet one which will be exceedingly effective for the purpose for which it is designed.

These and other objects I accomplish by means of such structure and relative arrangement of parts as will fully appear by a perusal of the following specification and claims.

In the drawing similar characters of reference indicate corresponding parts in the several views:

Figure 1 is a side elevation of the implement, with the jaws wide open.

Figure 2 is a fragmentary sectional view of the implement, with the jaws fully closed.

Figure 3 is an enlarged cross section on line 3—3 of Fig. 2.

Referring now more particularly to the characters of reference on the drawing, the implement comprises an elongated lower handle 1, and integral with the handle at its forward end is a vertically narrow flat portion 2, said portion terminating in a relatively narrow, parallel-sided cutting bar or fixed jaw 3 having a chisel-shaped sharpened tip 4.

The upper surface of the jaw 3 is formed with a slight concave curvature, while its lower surface is convexly curved. The longitudinal plane of this jaw lies in a plane adjacent and generally parallel to the longitudinal plane of the handle.

The handle 1 is formed at its rear end with a round head or knob 5 adapted to engage the palm of the hand of the operator when exerting the necessary longitudinal pressure on the implement to start the same under the cast.

The portion 2 adjacent but rearwardly of the jaw 3 supports a transverse pivot pin 6 on which a movable jaw 7 is pivotally mounted. This jaw 15 is of double or slotted form, the sidewalls 8 of which closely straddle the portion 2, and the jaw 3 when said movable jaw 7 is closed. The movable jaw 7 includes a cross web 9 at its forward end, the lower back edge of which cross web is 20 sharpened and forms a transverse cutting blade to cooperate in punching relation with the tip 4 of the jaw 3, as shown in Fig. 2.

The sides 8 of the jaw 7 are exteriorly bevel-sharpened along their lower edges, as at 10, to 25 cooperate with the side edges of the jaw 3, while the inner faces of said sides 8 are flared at the top, as at 11, to provide for clearance or relief of the cut-out ribbon of the cast.

A boss 12 is formed integral with and projects 30 upwardly from the portion 2 through the slot of the jaw 7 intermediate the pin 6 and the rear end of jaw 3. An upper handle 13 is forked at its forward end and is pivoted, as at 14, on the boss above the jaw 7; said fork being formed 35 with transversely spaced depending cams 15 which correspond to and engage the upper edges of the slotted jaw 7.

These cams are positioned, relative to the handle 13 and pivot 14, so that when said handle is 40 relatively close to the lower handle 1, the jaws are fully closed, as shown in Fig. 2. When the upper handle is raised and swung forward, the upper jaw 7 is opened by means of links 16 connecting the cams 15 and jaw 7 on opposite sides 45 of the implement. The links 16 may be of light construction, since there is no pressure to be overcome with the opening movement of the boss.

When the implement is in use the handle 13 is 50 first thrown up and forwardly to open the upper jaw 7. The lower jaw 3 is then inserted a short distance under the cast. Due to the thinness of the jaw 3 this may be done without hurt to the patient. While maintaining the handle 1 and jaw 3 stationary, the handle 13 is then 55 pulled back and down, causing the jaw 7 to move

in a closing direction, the sharpened lower edges 10 of the sides 8 of jaw 7 cooperating with the upper edges of the jaw 3 to shear through the cast, cutting out a ribbon which passes through the slot of the jaw 7. If it is desired to completely sever the cut ribbon the jaws are fully closed so that the ribbon is cut transversely and punched out by the cooperating tip 4 of blade 3 and transverse cutting blade of the cross web 9. If it is desired to leave the ribbon connected to the cast, the closing movement of the jaws is halted before the transverse cutting and punching-out action takes place. After each cut is made the lower handle and jaw are, of course advanced, and the cutting cycle repeated.

The form and relationship of the jaws enables the line of cut through the cast to be straight, or to follow a generally curved line, so that any particular section of the cast may be removed therefrom if desired.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A cast cutting implement comprising a lower handle and jaw unit, the jaw being rigid with and projecting forwardly from the handle, an initially separate, upper yoke-like jaw pivoted on the unit adjacent the rear end of the lower jaw for movement relative to the latter, an initially separate upper handle pivoted on the unit 40

independently of the upper jaw, and operating means between the upper handle and upper jaw to open and close the latter and arranged so that when said jaw is open, the upper handle is in an 5 upstanding position relative to the lower handle; the upper handle being pivoted on said unit above the yoke-like jaw and ahead of the pivot thereof, said operating means comprising a pair of transversely spaced cams on the upper handle 10 below the pivot thereof and engaging the upper surface of opposite sides of the yoke-like jaw to close the same upon rearward and downward swinging movement of the upper handle, and a link connecting the upper handle and upper jaw 15 to open the latter upon upward and forward swinging movement of the upper handle.

2. A cast cutting implement comprising a lower handle, a lower jaw mounted in rigid unitary relation with and projecting forwardly from 20 said lower handle, an elongated upper jaw facing downwardly and straddling the lower jaw, means pivoting said upper jaw adjacent its rear end on the lower jaw for cooperative opening and closing movement relative to the latter, a rigid boss projecting upwardly from the lower jaw adjacent its rear end, an upper handle having a fork at its lower end, the fork straddling said boss and being pivoted thereto for swinging movement of said upper handle about an axis parallel to but above the axis of the upper jaw, 25 cams formed on the opposed legs of said fork for cooperative engagement with the upper surfaces of opposite sides of the upper jaw, said cams being disposed to forcefully close the upper jaw upon rearward and downward swinging of the upper handle, and separate means connecting the upper handle and upper jaw to open the latter upon upward and forward swinging movement of said upper handle.

ARTHUR J. HOOD.
